UNITED STATES PATENT OFFICE.

JOSEPH MOSES WARD KITCHEN, OF EAST ORANGE, NEW JERSEY.

UTILIZATION OF CARBONACEOUS WASTES.

1,127,777.

Specification of Letters Patent.

Patented Feb. 9, 1915.

No Drawing. Original application filed April 3, 1909, Serial No. 487,694. Divided and this application filed July 22, 1913. Serial No. 780,528.

To all whom it may concern:

Be it known that I, JOSEPH MOSES WARD KITCHEN, a citizen of the United States, residing in the city of East Orange, county of 5 Essex, State of New Jersey, have invented new and useful Improvements in the Utilization of Carbonaceous Wastes, of which the following is a specification.

The present application is a division of and 10 continuation from my application Sr. No. 487,694, filed April 3, 1909, which matured into Patent No. 1,094,390, which application comprised a number of specific inventive ideas which under Patent Office ruling were 15 not allowed to be claimed in one application.

The basic idea of the present invention is to so treat, handle and burn certain carbonaceous matters that have been little or not at all used, and hence, which can be considered as fuel wastes, in such manner, that their utilization will be secured. Such wastes would include fine coal dust, bituminous slack, lignite, anthracite cinders, coke, and some very hard coals.

25 The invention comprises the ideas of transferring the energy in such fuels into electric energy, through the agency of the internal combustion engine, and through the agency of steam power developed from the 30 burning of these fuels. The reclamation of one of the referred to fuel wastes would comprise a method of screening and sorting unconsumed carbon from anthracite ashes, the largest part of the bulk of which is composed of unburned cinders from which heat has driven tar and sulfur. Another method of reclamation would be the coking of a bituminous fuel, the utilization of some of the volatilized products of the coking process, and the use of the coked coal in my 40 method.

The invention also comprises the method 45 of preparing these fuel wastes in such manner as to secure a proper passage of air and other gases with uniformity through such fuels when in mass, during their combustion; and to secure so perfected a combustion in their burning, as to develop the largest amount of available energy from such 50 wastes in the production of motive force. It will be remembered that in the combustion of all fuels, they are first gasified prior to their burning.

In carrying out the purpose of this inven-

tion, I designedly use a thick fuel bed, 55 whether in producing gas to be used in the internal combustion engine or in producing gas that is burned in a furnace for generating steam in a boiler from the heat generated. Using such a thick bed of fuel, I 60 gasify that fuel into a composition comprising a considerable amount of carbon monoxid, which is burned through its admixture with an accurate proportion of the amount of air needed to secure a perfected 65 combustion of the carbon monoxid gas. The heat thus generated from the burning of the gas may be used to generate steam alone, or it may be used for expansive purposes in the internal combustion engine; or the two 70 applications for the gas may be made in securing motive force. To secure the full aim of the invention the gas is finally converted into electric energy, and in that form is distributed and applied in work. Such 75 applications of fuel gas are indicated in U. S. Patents 888,809, 992,780, 1,041,810 and 1,063,880 issued to me.

It will be understood that the full invention consists of coactive steps in reclaiming 80 a fuel waste, in preparing that fuel waste in such manner as to secure its effective gasification, in providing for the complete burning of the fuel in its gaseous state, in securing its change into motive power, and the 85 mutation of that motive power into a convenient form in which the energy may be distributed and applied in work with the greatest economy, which last form is preferably the electric current. All these steps 90 are required to make the utilization of the fuel waste economically worth while.

Note should be here made that although all fuel is gasified before burning; in the present invention, I secure a more complete 95 performance of the gasifying process.

In older methods of securing a perfected transfer of the energy in the fuel into motive power, great losses have occurred. Take, for example, the burning of bituminous coal. It has been the common practice to burn it in a thin layer, with the production of much smoke, the occurrence of considerable losses through grate siftings, and the escape of much unconsumed carbon 100 monoxid gas. Also, there has usually been more or less loss due to dilution of the gases 105 with too much air for combustion, with con-

sequent defective transmission of energy. My method overcomes these and other disadvantages of older methods.

In connection with the use of fuel, there are certain parts of special fuels that frequently are only partially burned in use; or else, because of particular characteristics, such fuels are not used at all. In the mining and use of anthracite coal, great amounts of fine dust are formed and discarded. Immense amounts of anthracite cinders are thrown away in ashes. These cinders are formed by the action of ashes surrounding the fuel particles, which exclude air from the unconsumed carbon of the fuel particles, and from which particles, volatile, tarry, sulfurous and hydrogen elements have been driven by the environmental heat of the entire fuel-mass. Of the ashes from anthracite coal, on an average, about 50% of its bulk is unburned carbon in the form of a coked fuel of many sized particles that are substantially free from sulfurous, tarry and hydrogen compounds. This unconsumed carbon is hard in texture and somewhat difficult to burn under atmospheric pressure alone; and it is a question whether it will ordinarily pay to reclaim cinders from publicly handled ash accumulations for ordinary combustion purposes.

One object of this invention is to provide in part, a plan or method through which cinders as well as other fuel wastes, can be utilized in a manner economically worth while practising.

There are also certain very hard fuels that are difficult to burn. Such hard fuels, and anthracite cinders and coke, if they are properly and thoroughly admixed with finer and softer fuels, more rich in easily volatilized elements, will produce an admixed mass of a character which allows for a thorough gasification of the admixed mass, and its subsequent complete burning.

My invention comprises the idea of preparing or reclaiming a porous hard fuel like anthracite cinders or coke, mixing such prepared or reclaimed carbonaceous matters with softer and finer fuel like bituminous slack, or fine anthracite dust. I also admix hard uncoked fuels of somewhat large size as to their fuel-particles, with softer and finer fuels. In a thick fuel-bed mass of such admixed fuels, during the heating and gasification of the mass, the harder coal becomes gradually coked as the harder particles gravitate to the fire-grate level, an envelopment of ashes around the hard fuel particles preventing air from freely reaching the hard particles; which condition tends to coke those harder particles, rather than to immediately entirely consume them. In this way the entire fuel mass is rendered more porous, and better suited for the purposes of complete gasification of the entire

mass; and ultimate complete combustion of the part of the fuel mass that is at a low level in the furnace. By handling a thick fuel-mass in this way, and admitting only enough air for complete combustion of the lower zones of the fuel mass, under and through it, the fuel mass is completely burned at the lower zone level, but with development of heat, which acting at a high level; results in the evolution of a large amount of burnable CO gas in the upper zones of the fuel mass, and which after its passing through and leaving the fuel-mass, can be completely consumed by a positive and accurate admixture of air-for-combustion with the still unburned gas. If the gas is to be used in the internal combustion engine, its contaminating tarry and sulfurous vapors are removed, preferably by super-heating the gas, and then washing it.

If the gas is to be directly used in generating steam, it is merely burned in its crude, unpurified form, in or under the steam boiler. It, however, is then burned with a correct proportion of air-for-combustion: and preferably, with air that is maintained in a mechanically produced state of compression, as is illustrated in my U. S. Patent No. 1,046,308.

Besides large wastes which occur in connection with the use of anthracite fuel, there are enormous deposits of bituminous and lignite coals that are not used at present, but which can be utilized through the performance of the present invention. The utilization of such fuels would include the process of coking a part of them, utilizing the gases produced by such coking as fuel gas after preferably preliminary treatment of super-heating and washing. This gas can be applied in various lines of work such as heating and motive power production. In carrying out this utilization method in the best manner, a considerable amount of specially designed apparatus is required for use in securing the aimed for result; such as means for screening and sorting fuel, conveniences for thoroughly admixing fuels, special gasifying apparatus, gas pumps, mechanical draft producers, a superheater for cleaning the gas, and various heat economizing devices. A specific description of these various structures is not needed in describing the present invention; but the inventive ideas claimed for the present invention, comprise coöperative performances of certain combinations of steps the interdependent coöperation of which are needed to secure the aimed for result. It should be noted that in order to secure an economical utilization of what is herein designated as fuel wastes, special means and methods have to be adopted to secure sufficiently satisfactory results; whereas, under ordinary practices, it would usually not be worth while to

reclaim and use such wastes. In cinders and in ordinary gas house coke, there is such a lack of concentration of heat forming constituents, that it is ordinarily not worth 5 while using them alone; inasmuch as the volatilization of such fuel-wastes under ordinary methods, produces gas that is poor in heat values. But by adding low cost fine fuel dusts, rich in heat values, in properly 10 proportioned admixture, with the more porous and harder fuels, we secure a fuel mass that gasifies well and produces a richer gas, and more intense heat when burned. In some cases, the process of coking the fuel 15 and gas produced from it, may be continuously effected in a producer, or the furnace in which the admixed fuels are being gasified.

While the present invention may be used 20 in generating producer gas for the various uses of that gas, it is of particular value in the generation of heat to be used in generating steam, in developing the electric current in the thermo-pile, and in various other 25 applications in which sensible heat may be economically applied.

In particular, I draw attention to my method for securing an efficient burning of the gasified fuel. As such gasified fuel is 30 usually deficient in its proportion of heat forming constituents, because of admixtures with nitrogen and carbon dioxide gas, it is particularly important that in its burning no more air-for-combustion be admixed with 35 it in its burning, than is necessary for union with the unburned constituents in the gas. Dilution with excessive air is a very widespread source of economic loss in the burning of fuels for motive power generation, 40 and other uses. Such dilutions result in gaseous admixtures having a less intense degree of heat than would be the case if the dilution were avoided. This is an ill that should be prevented, inasmuch as burned 45 gases of low intensity of heat do not transmit such low degrees of heat so thoroughly and so quickly as they would if they were of a higher intensity. If gases poor in thermic constituents are much diluted with air, they 50 cannot be burned at all, unless highly pre-heated from an outside source, because the excessive air dilution prevents the attainment of, or holding of the temperature in the gas that is sufficiently high to allow of 55 combustion. In this case it is very much like throwing water on flame. There is a cooling effect. The securing of combustion necessitates the attainment of a so-called "critical" temperature, which is usually in 60 the neighborhood of 1300° F. but which varies according to the character of the material being burned.

In burning the gasified fuel which I generate, I either burn it by forcing it against 65 air without previous dilution before its

burning, or else I burn it in a confined space under pressures more or less higher than atmospheric pressure. In its burning under a steam boiler, such pneumatic pressure may vary from a pressure represented by one 70 water inch, up to eight or more water inches. In the internal combustion engine, the pressure may be up to 200 pounds per square inch or more. In general, it may be said, that the poorer the gas that is to 75 be burned, the higher the pressure may be under which it is burned. Very rich gases, which are usually expensive gases, can not be so economically used on this account in the internal combustion engine as gases 80 poor in thermic units. A gas thermically poor, such as I produce, of a richness approximating that which would be represented by 100 B. T. U.'s, is fully as effective in an internal combustion engine 85 as a gas of a richness of 500 B. T. U.'s, the latter gas probably costing twenty times as much or more to make, simply because the rich gas can not be brought to so high a degree of compression as the poorer quality 90 of gas, without inducing a premature explosion or burning. For this reason, when fuel used is high in price, it may be economical to utilize it through the internal combustion engine, notwithstanding the 95 complexity attending upon the preparation from the fuel of a gas suitable for that purpose. But when fuel is low in price, it is more simple and economical to burn it *in situ* under boilers for steam generation, 100 rather than to carry out the full process of preparing the gas in such manner as to make it a satisfactory fuel for the internal combustion engine. Cheap fuels are likely 105 to be those which easily form smoke in their burning; and as my method is very advantageous in preventing smoke formation, the use of such cheap fuels will usually be found to be best through their utilization 110 in the generation of steam. In all cases, however, I consider that the movable transfer of the energy resident in the fuel-waste into a vendible and practically usable electric current, is the ultimate ideal aim of 115 the invention. Energy in one form is in the fuel waste; but the same energy undergoing successive changes in the process steps of the invention becomes the aimed-for 120 economically utilizable product. It is in this way that the enormous deposits of fuel-wastes now in existence, can be most efficiently and beneficially applied in practical uses in cities and other points of distribution.

Having now described my invention, what I claim as new is:

1. The method of utilizing fuel wastes herein described, which consists in, (1) admixing a hard fuel that is relatively free from easily volatilized constituents with a

softer fuel containing a relatively large amount of easily volatilized constituents, (2) inserting a thick bed of admixed fuel in a furnace, (3) completely burning a part 5 of said fuel by the aid of a forced draft of air, and volatilizing another part of said fuel, whereby through said volatilization a burnable gas is evolved, and (4) admixing in accurate dosage air and the 10 evolved burnable gas and burning the admixed air and burnable gas, said last named step being performed under a controlled pneumatic pressure.

2. The method of utilizing fuel wastes 15 herein described, which consists in, (1) reclaiming a coked porous fuel from which easily volatilized burnable constituents have been driven by heat, (2) gasifying the fuel under a controlled forced and under a con- 20 trolled induced pressure, (3) superheating the gas, (4) washing the gas, and (5) burning the gas under controlled pressure in combination with air in proper proportion to secure a complete combustion of the gas 25 but without surplusage of such air.

3. The method of utilizing fuel wastes herein described, which consists in, (1) cok- 30 ing fuel, (2) producing a burnable gas from the coked fuel, (3) enriching the gas with burnable constituents, and (4) burn- 35 ing the enriched gas with air under a me- chanically produced pneumatic pressure.

4. The method of utilizing fuel wastes herein described, which consists in, (1) 35 forming a thick bed of fuel, (2) burning a part of the fuel and mechanically forcing the gaseous products of said burning

through the balance of the thick bed of fuel, whereby burnable gas is generated, and (3) burning the burnable gas in contact with 40 air mechanically forced but not in excess of air required to secure the combustion of the burnable gas, said burning being ef- fected under a controlled pneumatic pres- 45 sure higher than atmospheric pressure.

5. The method of utilizing fuel wastes herein described, which consists in, (1) forming a thick fuel bed of an admixed hard porous fuel and a finer more compact fuel-material containing richer and more 50 easily volatilized burnable constituents than is contained in the hard porous fuel, (2) gasifying the thick bed of admixed fuels through the application of heat, (3) burn- 55 ing the gasified fuel in combination with air that is not in excess of the amount of air needed for combination with the burn- able constituents in the gasified fuel, (4) generating from said burning a form of energy capable of application in work, and 60 (5) distributing that form of energy in work.

6. The method of utilizing fuel wastes herein described, which consists in, generat- 65 ing producer gas from such fuel wastes, burning said producer gas by forcing said gas in a state of high heat against air, but without admixture of air with the gas be- fore its burning.

JOSEPH MOSES WARD KITCHEN.
